DESIGN FOR A VENDING MACHINE CASING

Charles J. Gilmer, Atlanta, Ga., assignor of
one-half to Harry P. Woodward, Atlanta, Ga.

Application June 12, 1933. Serial No. 48,378

Term of patent 7 years

To all whom it may concern:

Be it known that I, CHARLES J. GILMER, a citizen of the United States, residing in Atlanta, county of Fulton, and State of Georgia, have invented a new, original, and ornamental Design for a Vending Machine Casing, of which the following is a specification, reference being had to the accompanying drawing, forming part thereof, in which:

Figure 1 is a perspective view looking at the front and one side of the vending machine casing; and

Figure 2 is a perspective view looking at the rear and the opposite side of the vending machine casing.

I claim:

The ornamental design for a vending machine casing, as shown.

Signed at Atlanta, county of Fulton, and State of Georgia, this 30th day of May, 1933.

CHARLES J. GILMER.
